UNITED STATES PATENT OFFICE

2,546,327

SPOUT, HOOD, AND MIXING CHAMBER FOR
SANITARY FIXTURES

Stephen A. Young, Delphi, Ind.

Application July 31, 1945, Serial No. 607,942

1 Claim. (Cl. 4—192)

1

This invention relates to a lavatory or sink or like fixture with or without drain control accommodation.

The chief object of this invention is to provide an ornamental hood or shell which is integral with the spout and associate the same with hot and cold water valve controlled supplies, in such a manner that the resulting hood and integral spout is not subject to strain, thereby permitting the use of zinc, brass or white metal castings for such hood and spout. This in turn insures the casting of exceedingly smooth finished products that are readily capable of plating if of metal, and furthermore, since strains are eliminated, the ornamental hood or shell and integral spout may also, when desired, be made of variously colored plastic materials for such uses where color is desired.

Heretofore in the art the ornamental unit including the spout and the two water supply connections, as well as the mixing chamber, required great care in casting, including special coring and the like. This was necessary because the unit itself constituted a portion of the water supply arrangement. Blow holes and like imperfections in the resulting castings were frequent, and production loss, as well as unit time of production, was excessive.

Accordingly, the present invention eliminates the loss due to porosity in foundry work, always prevalent when made from sand castings, and the resulting bottle neck in production.

The present invention is directed to the utilization of a rough element for the water supply and mixing chamber which is subject to strain, but since it is not to be highly finished and is to be concealed by the ornamental hood, does not require the care heretofore required with the structures known in the art. Associated with this rough unit is the combination ornamental hood and integral spout and which can be mounted without strain.

The chief feature of the present invention resides in associating an ornamental hood and combined spout with a rough unit multiple water supply and mixing chamber, said hood being provided with openings for valve exposure.

A further feature of the invention resides in the non-interfering or offset formation of the multiple water supply and mixing chamber rough unit, and its association with a combination spout and cover hood or shell having the desired ornamentation or outline, the latter supporting a drain control in juxtaposition to the aforesaid rough unit.

2

Other objects and features of the invention will be set forth more fully hereinafter.

The full nature of the invention will be understood from the accompanying drawings and the following description and claim.

In the drawings Fig. 1 is a longitudinal central sectional view in the central plane common to two parallel water supplies.

Fig. 2 is a transverse sectional view taken in the central plane including the spout.

Fig. 3 is a top plan view thereof.

Fig. 4 is a bottom plan view of the spout and rough unit casting.

Fig. 5 is a central sectional view looking away from the spout and of the drain control accommodating embodiment of the invention.

In the drawings, and more particularly Figs. 1 and 2, there is illustrated the top of a lavatory or sink 10 having a bowl or basin portion 11, and

20 the same is provided with suitable apertures 12 of the desired spacing and a central aperture 13. The aperture 13 is provided for drain controlled mechanism accommodation, not shown in Figs. 1 to 4 inclusive.

25 Extending and herein upwardly through the openings 12 are two externally threaded tubes 14 to which the hot and cold water supplies are connected beneath the support portion 10. Positioned above this portion is the valve chamber 15 and the two inwardly and angularly directed tubular portions 16 that merge together in the junction 17, see Fig. 4, the portions 16 and 17 forming a mixing chamber.

Extending upwardly from the valve and opposite the tubular portion 14 is the tubular portion 18 having external threads 19 and an internal coarse thread 20. The chamber forming portion 15 at its junction with the tubular portion 14 forms a valve seat 21, and associated therewith is the valve member 22 adapted to

35 have secured thereto the conventional seal 23. The valve member 22 has a stem 24 that projects upwardly beyond the tubular portion 18 and is enlarged laterally within the same and provided with a coarse thread 25. The free end of this stem 24 may be serrated as at 26 and thereon may be mounted in the usual manner a valve handle.

A cap 27 has threaded connection 28 with the threads 19, and the internal shoulder 30 of the cap bears upon the washer 31 engaging the outer upper edge 29 of the tubular portion 18. Packing 32 may be included between the washer and the head of the cap which is apertured at 33 to 45 pass the stem.

When the handle is turned, the seal 23 is removed from seat 21 or brought into engagement therewith, and by this means the valve regulates cut-off, full flow or partial flow from the tube 14 to the communicating conduit portion 16. 5 This structure, except for the valve, washer, packing and cap is unitary and a rough unit.

The shell includes a top 40, a front portion 41, a back portion 42 and the two ends 43. The top is apertured as at 44, and the tubular portion 18 10 extends freely through said aperture. If desired, a valve chamber portion 15 may be shouldered as at 34 to permit the cover or shell to bear thereon, although this is not essential.

Extending upwardly and forwardly from the front 41 and integral with the cover is a spout 45 having a downwardly directed discharge outlet 46 at its forward end and an internally threaded portion 47 at its opposite end. This spout portion has an annular face 48 concentric 20 with axis of the threaded aperture 47. The threaded aperture 47 is laterally enlarged as at 49.

The junction 17 of the rough unit has an annular face 50 confronting face 48 and a tubular 25 extension 51 that extends into the counterbore 49. The junction 17 opposite the tubular portion 51 is apertured as at 52. Interposed between the two confronting faces 50 and 48 is the gasket 53. Note gasket 54 is applied to the opposite face 56 30 of the junction 17.

A connector device includes a screw bolt member having the screw head portion 57 and the tubular body portion 58, externally threaded as at 59 and provided with a plurality of apertures 60, has an exterior bore 61 that closely fits the central bore through the junction 17 as previously described. The threaded end 59 of the tubular bolt has threaded engagement as aforesaid with the base of the spout, and by this means 40 the spout and the rough unit are rigidly connected together in leakproof relation. Furthermore, the apertures 60 in the tubular bolt provide communication between the spout and the interior of the junction 17.

It will be obvious, therefore, that by properly locating the position of, let us say, shoulder 34 with respect to the surface of the base or support 10, that no strain whatsoever will be placed upon the combination cover and spout fixture, and yet 50 the cover at its lower edge can just bear upon said support 10. This cover conceals the rough unit and masks the openings in the support.

Obviously the opening 13 in the support is of such character that access can be had to the tubular bolt 57 to effect the desired connection 55 between the spout with its attached cover and the rough unit previously described.

Reference will now be had to Fig. 5 wherein a modified form of the invention is illustrated.

In this form of the invention numerals of the one hundred series designate parts identical or similar to parts designated by the primary numeral series and illustrated in Figs. 1 to 4.

In this form of the invention the drain controlled structure is associated with the junction portion, and this drain controlled structure is associated with a detachable spout. The junction 117 includes an upwardly directed tubular portion 160 which is internally threaded as at 161 and enlarged laterally to form a shoulder 162 70 to take a gasket 163, and this counterbore is internally threaded as at 164 to take the threaded portion of a gland nut 165 bearing on a washer 166. The gland nut and gasket envelopes the

stem 167 of the base of a spout having a large chamber forming portion 168 with which the spout 145 communicates. A gasket 169 and a gland nut 170 have threaded engagement as at 171 with said portion 168 at 172.

A stem 173 mounting an exposed knob 174 is reciprocable or rotatable as desired for drain control purposes. The stem 173 is of lesser cross-sectional area than the tubularity of the portion 167, the latter having threaded engagement as at 16a with the threaded portion 161.

The top 140 of the cover is apertured as at 175 and a masking and ornamental collar 176 envelopes the projecting tubular portion 160 of the rough unit and masks the opening in the cover as shown, said collar being retained by its flange 177 being interposed between the gland nut 165 and the end of the portion 160. The junction 117 opposite the tubular extension 160 includes an inwardly directed portion 180 apertured at 181 to pass the rod 173. This inwardly directed portion is threaded as at 182 and a gland nut 183 bears upon gasket material 184 between the nut and the portion 180, the gland nut and packing material being apertured for rod accommodation, and when the nut is tightened, a leakproof connection is effected.

The third modified form of the invention obviously is one wherein the cover 49 in Figs. 1 to 4 inclusive is centrally apertured as shown by the dotted lines 200 in Fig. 1, and inasmuch as the conduit portions, see Fig. 4, are divergently directed, the rod following spout and cover connection to the rough unit may be slidably and/or rotatably supported in the opening 200, the rod at its lower end being suitably connected to a drain which may, if desired, be of pop-up character.

It will be clearly understood that all supply pipe strains are incorporated in the rough unit and are not transmitted to the combination cover and spout, so that the latter can be a brass forging (brass if desired), a die casting (brass, zinc or die metal) or of plastic or other suitable material having a low tensile strength, and to which a smooth finish can be imparted in the casting operation, so that such a cover, if die cast metal, can be subsequently plated, etc. without any great cost or labor.

This invention as initially stated herein eliminates the smoothing operations required in the prior art structures, eliminates the wastage incident to blow holes and the like, and furthermore, the speed ratio of production has been ascertained to be approximately 20 to 1, that is, 20 covers and integral spouts, while 1 of the prior art units is being fabricated to a finished condition.

While the invention has been illustrated and described in great detail in the drawings and foregoing description, the same is to be considered as illustrative and not restrictive in character.

The several modifications described herein as well as others which will readily suggest themselves to persons skilled in this art, all are considered to be within the broad scope of the invention, reference being had to the appended claim.

The invention claimed is:

In a valve structure for mounting in exposed relation relative to an apertured support, the combination of a one-piece rough unit having spaced parallel connecting portions for connection to separate supply pipes, each connecting portion including a chamber for valve accommo-

dation, two conduits directed from the chambers and towards each other, and terminating at a junction, a chambered cover having valve accommodating apertures, a spout portion and spout for the unit and cover respectively and having adjacent ends registering, and means connecting the cover to the unit at the junction, the cover nesting and concealing the support exposed unit, the spout being detachably associated with the junction and the cover and support being apertured midway between their respective valve accommodating apertures, and a drain valve control rod movably mounted in the midway apertures for drain control purposes and extending through the junction and spout and 15 the connection therebetween.

STEPHEN A. YOUNG.
